JOHN S. CRAWFORD, OF NEW LONDON, CONNECTICUT.

AUTOMATIC TRAIN CONTROL.

1,362,927.

Specification of Letters Patent. Patented Dec. 21, 1920.

Application filed December 26, 1917. Serial No. 208,779.

To all whom it may concern:

Be it known that I, JOHN S. CRAWFORD, a citizen of the United States of America, residing at New London, Connecticut, have 5 invented a new and useful Automatic Train Control, of which the following is a specification.

This invention relates to the automatic control of railway trains, and has for its objects the provision of reliable and efficient 10 mechanism for automatically controlling a train in the presence of danger conditions.

Special objects are to provide simplified 15 and improved mechanism for automatically shutting off the power and applying the brakes.

Another important object is to bring about both "service" and "emergency" applications of the brake to meet existing conditions. 20

The invention is designed to be applied to and used in conjunction with the usual air brake systems and briefly stated comprises a control valve adapted to be operated by a 25 so-called "cam" or obstruction provided on the trackway and which when so actuated permits pressure from the train pipe to actuate a valve for shutting off communication between the main reservoir and engineer's 30 valve, said train pipe air being thereby vented to bring about an application of the brakes. This shut-off valve when so actuated serves to open up a flow of fluid under pressure from the main reservoir to a pressure 35 operated power controlling member, and also provides for a flow of actuating fluid to restore the control valve to its original condition.

Other features of the invention are a 40 special cut-off valve for rendering the automatic system inoperative when the engineer is exercising the proper control over the train, an automatic pressure control valve for effecting the proper application of the 45 brakes, and special electro motor mechanism for operating the cam or track device.

Other features of the invention will appear as the specification proceeds, attention being now directed to the accompanying drawings which illustrate the invention embodied in a practical working form. 50

In said drawings:—

Figure 1 is a more or less diagrammatic representation of my automatic control sys-

tem as applied to a steam railway, the several parts of the apparatus being for the most part shown in section to better illustrate their construction and operation. 55

Fig. 2 is a cross sectional view of the service and emergency control valves; 60

Fig. 3 is a sectional view of the same valves as shown in Fig. 2, but taken in a plane at right angles to that of Fig. 2; 65

Fig. 4 is a sectional detail view of a swivel joint; 70

Fig. 5 is a sectional view showing the throttle latch releasing means; and 75

Fig. 6 is a fragmentary sectional view of a part of a compensating or automatically adjusting valve. 80

The numeral 7 designates the train pipe or train line of a typical air brake installation, 8 indicating the main reservoir and 9 the engineer's valve of such system, said engineer's valve being disposed as usual in a pipe connection 10 between the main reservoir and train pipe. 11 designates the power controlling member, which in the case of a steam railway is illustrated in the form of a throttle lever. 85

The control valve is indicated at 12 and the shut-off valve is indicated at 13. 90

Specifically the control valve comprises in the present disclosure a cylinder 14 within which there is mounted a valve piston 15 controlling an inlet 16 and an outlet 17, said piston being mounted on a protruding piston rod 18 carrying a roller 19 at its lower end for engagement with the track cam. This latter element is designated 20 95 and may be in the form of a short rail section or ramp disposed between the tracks in position to engage when raised with the trip roller 19. 100

The cam or tripping device is actuated in the present illustration by an electric motor comprising an armature element 21 mounted on a vertically reciprocating plunger 22 and working within a relatively stationary field magnet structure 23. The cam 100 is mounted on the upper end of the plunger 22 and this vertically reciprocating structure may be counter-balanced by a weight 24 adjustably engaged on the end of a pivoted lever 25 which is shown pivotally engaged with the lower end of the plunger. 105 The electrical connections, as will later be pointed out in detail, are such that at one

time the armature and field will be energized to attract one another and under reverse conditions will be energized to repel each other.

5 The main shut-off valve 13, as here disclosed, consists of a cylinder 26 within which works a piston 27 carrying a valve 28 for engagement with a valve seat 29, the latter being disposed in a passage forming part 10 of the connections between the main reservoir and engineer's valve. The shut-off valve piston 27 also controls a vent 30 to atmosphere.

15 The control trip operated valve is connected at its inlet side 16 by piping 31 with the train pipe and is connected at its outlet side 17 by piping 32 with the cylinder 26 of the shut-off valve.

20 From the construction thus far described it will be apparent that when the trip roller on the controller valve encounters the up- 85 raised cam 20, said valve will be lifted, upwardly opening communication between the inlet and outlet ports 16—17 and permitting a flow of air from the train pipe through pipe 32 to the head of the actuating piston 27 of the shut-off valve. This piston will be thereupon actuated to carry the valve 28 to its seat thereby cutting off 90 communication between the main reservoir and engineer's valve. The piston in this movement uncovers the vent 30 thereby permitting the train pipe air to escape by way of said vent, this resulting in an application 95 of the brakes.

35 The force for cutting off the steam or other power is supplied in my present disclosure from the main reservoir through pipe 33 by-passed around the shut-off valve 40 and under the control of a valve 34 which in turn is under the control of the shut-off valve. This air supply valve 34 is shown directly connected with a piston 35 working in a cylinder 36 which latter may be 45 made as an integral part of the main shut-off valve. The top of cylinder 36 above the head of the piston therein is connected by a port 37 with the shut-off valve passage 38 so that when the shut-off valve is 50 open, as it is under normal running conditions, valve 34 will be held closed by the main reservoir pressure on top of piston 35. When however the shut-off valve is actuated as above described, to close off communication between the main reservoir and engineer's valve, the port 37 will be covered by the stem portion 39 of valve 28 and pressure on top of piston 35 will be thereby removed. The remaining pressure on top 55 of piston 35 is vented at such times by way of a vent port 40 provided in the cylinder above the piston and connected by piping 41 with a port 42 opening into the cylinder 26. This port 42 is normally covered by the 60 piston 27 but when said piston is moved over 65

as above described to close the shut-off valve, said port is opened and the pressure on top of cylinder 35 can thereby escape through piping 41 and port 42 out the then-opened vent 30.

70 When the shut-off valve has been closed and the pressure on top of piston 35 thus relieved, the air supply valve 34 opens under influence of the main reservoir pressure supply beneath the same through piping 33 and permits flow of air at said reservoir pressure through port 43 and by way of piping 44 to a point beneath the piston 45 in the throttle closing cylinder 46. This piston is connected by a piston rod 47 80 with the rearward end of the pivoted throttle lever so as to impart a closing movement to the throttle.

85 To enable this closing movement the throttle latch must be released and this is accomplished in the case illustrated by a throttle lifting piston 48 connected with the latch rod 49 and working in a cylinder 50, said cylinder being supplied with actuating fluid through branch piping 51 connected with the 90 supply pipe 44. A swivel joint is provided in this branch line to allow for the pivoting movement of the throttle lever, said joint comprising a chambered member 52 mounted on the throttle, to which the piping leading to the latch lifting cylinder is connected and which is provided with a passage 53 concentric with the pivotal axis of the throttle in which is rotatably engaged the end of the branch piping 51 leading from the supply 100 pipe 44.

95 In the present illustration the control is exercised from the track signals by means of switches operated by the semaphore arm and controlling operation of the cam lifting motor. 54 designates the semaphore or track signal carrying a control arm 55 supporting a series of switch contacts 56, 57 and 58 for bridging contacts 59—60; 61—62; 63—64 respectively. Contact 59 is connected by wiring 65 with the contact 66 within the housing 67 of the track motor, said contact being slidingly engaged by a brush 68 carried by the movable element of the motor and connected by wiring 69 with the armature 21. Contact 60 is connected by wiring 70 with one side of the stationary field winding 23 and contact 61 is connected by wiring 71 with the other side of this field winding. Contact 62 is connected by wiring 72 110 with one of the current supplying wires 73. Contact 63 is connected by wiring 74 with a contact 75 with which engages the sliding contact 76, connected with the other side of the armature. Contact 64 is connected by 115 wiring 77 with the other line wire 78.

120 When therefore the semaphore arm stands in the warning position shown in Fig. 1, the circuits will be established as follows: from line wire 73 through wiring 72, contact 62, 130

bridging contact 57, contact 61, wiring 71 through field winding 23 and by way of wiring 70 to contact 60, bridging contact 56, contact 59, wiring 65, contact 66, brush 68 and wiring 69 to the movable armature 21 and thence by connection 79, brush 76, contact 75, wiring 74 to contact 63 bridging contact 58, contact 64 and connection 77 to the other line wire 78. These connections are such as to cause the armature and field to repel each other and the cam to be therefore raised into the tripping position indicated.

When the track signal drops back to the "safety" position circuits are established as follows for effecting a reverse operation of the motor; bridging contacts 80, 81, 82 on the semaphore operated arm 55 connect contacts 83—84; 85—86 and 87—88 respectively. Under such conditions current flows from the line wire 73 through wiring 89 to contact 86 across bridging contact 81 to contact 85 and thence by wiring 90—71 to the first side of field winding 23, and by way of wiring 70—91 to contact 84 across bridging contact 80 to contact 83 and by way of wiring 92—74, contact 75, brush 76 and connection 79 to the opposite or reverse side of the armature 21 and thence by wiring 69, brush 68, contact 66 and wiring 65—93 to contact 87 and across bridging contact 82 to contact 88 and thence by wiring 94 to the return side 78 of the line. Under these so-called safety conditions the armature and field will attract each other and hence the cam will be lowered to an inactive position. The counter-balance weight 24 is usually so adjusted that in case of any electrical connections being broken, the cam will be automatically elevated.

The control valve 12 is designed to effect a service application of the brakes. When therefore said valve is operated by the cam elevated as just described, said valve will release the train pipe air at a rate such as to effect a so-called service brake application. This is accomplished by providing what I have termed a compensating or automatically adjusting valve 95 in the air connections between the train pipe and control valve. This compensating valve comprises a piston 96 working in the cylinder 97 and normally acted upon by the train pipe air, said piston carrying a slide 98 having a substantially diamond-shaped valve port 99 therein controlling a port 100 connected by the piping 31 with the control valve. When the full pressure train pipe air is upon piston 96, the piston will be forced downward so that the constricted upper end of the diamond-shaped valve port 99 will be disposed over the outlet port 100. Consequently, with the train pipe air at normal pressure, when the control valve is actuated the escape of train pipe air by way of cylinder 26 and vent 30 will at first be restrict-

ed to prevent too sudden an application of the brakes. Then, as the train pipe pressure is reduced by the venting thereof, the piston 96 in the compensating cylinder will rise under the action of the counter-balance spring 101, carrying the diamond-shaped valve slide upward to more fully open the outlet port 100. A gradual but at the same time complete application of the brakes is thus assured.

To insure the control valve being promptly returned to its original condition after it has been actuated by the trip cam, I have provided a connection 102 for supplying air under main reservoir pressure from supply pipe 44 to the head of the piston 15 of the control valve. Thus the control valve will be restored to normal operative position along with the shut-off of power.

After operation of the automatic stop mechanism the engineer may regain control of his train by opening the shut-off valve to again establish communication between the main reservoir and engineer's valve, this being accomplished by returning the shut-off valve to the position indicated in Fig. 1 by forcing in the handle 103 connected with the shut-off valve. When this is done air under reservoir pressure is again applied to the top of piston 35 which closes the air supply valve 34. The air from the throttle unlatching cylinder and control valve cylinder 14 in this case vent back through the pipe 44, port 43 and by way of an exhaust port 104 and vent pipe 105 into the cylinder 26 at 106 in front of piston 27 and thence out the vent 30.

To prevent duplication of the engineer's actions the automatic stop is automatically cut out of operation when the train is properly controlled by the engineer. Thus when the engineer, observing the signals set against him, reduces speed by applying the brakes, pressure in the train pipe is reduced and this effect is taken advantage of to render the automatic stopping mechanism inoperative. The means for this purpose here comprises a cut-out cylinder 107 interposed in the line of connections between the train pipe and control valve and having a spring pressed piston 108 therein acting as a valve to control the passage 109 between the said cylinder and the compensating cylinder. The train pipe air, connected by piping 110 with the head of the cylinder 107 forces said piston 108 over to open up communication between the train pipe and control valve by way of port 109. When however, the pressure in the train pipe is reduced by the engineer's application of the brakes said piston 108 is moved over by its counter-balance spring to close the port 109 and thus cut off communication between the train pipe and control cylinder 115 120 125 130.

valve. The operation of the control valve then will have no effect upon the system. When piston 108 thus moves over under the influence of its spring to close passage 109, 5 it also opens up a vent 111 permitting the escape of air from the compensating cylinder by way of cylinder 107 and a second vent 112 to atmosphere.

In addition to service stops the invention 10 is adapted to produce a danger or emergency stop when necessary. This may be accomplished by providing a second control cylinder 113 having a valve 114 therein provided with a valve rod 115 carrying a 15 roller 116 on its lower end for engagement with a so-called danger or emergency stop cam. This latter cam will be off-set to one side of the service stop cam, already described, and means similar to those described in connection with the service stop 20 cam will be provided for operating the same. The emergency stop control acts when operated to provide for a sudden release of the train pipe pressure to thus effect an emergency application of the 25 brakes. This is accomplished in the illustration by connecting cylinder 113 directly with the train pipe by a connection 117 and with the pipe 32 by connection 118, so that 30 when said emergency valve is operated the full train pipe pressure will be quickly vented by way of vent 30 of the shut-off valve.

The service and emergency stop control valves may be coupled together in a single 35 unit as indicated in Figs. 2, 3. Said valves may be separately tested before starting on a run by means of a test valve 119 which may be turned in opposite directions to provide flow through either pipe 120 or 121 40 to lift either one of the valves, pressure being supplied for this purpose by piping 122 connected with the main reservoir. Check valves 123 may be provided in these test connections 120, 121 to prevent escape of 45 train pipe air by way of these connections when the control valves are operated by the track trips.

The track motor which I have provided is particularly simple and sturdy in construction and therefore well adapted to the 50 uses for which it is designed. There is practically only one moving part, that is, the movable armature structure and the parts are all protected within the housing 55 shown. As a further protection, the armature structure may be covered by a bell-shaped dome or hood 124 carried by the plunger 22 and covering the armature and field and the sliding electrical connections 60 described. By adjusting the weight 24 the motor may be set to operate as desired.

The invention it will be seen is capable 65 of ready application to the train controlling and braking systems of trains now in use and it will be seen that on the whole

the invention comprises but relatively few and comparatively simple parts or mechanisms which are not likely to get out of order. The system furthermore is direct and positive in its action. The ability to 70 secure both service and emergency applications is of special importance. The compensating or pressure reducing mechanism used in connection with the service braking application is highly desirable as preventing sudden injurious application of the 75 brakes and an even setting of the brakes throughout the length of the train.

I claim:

1. An automatic train stop, comprising in 80 combination with the main reservoir, train pipe and engineer's valve of an air brake system, a control valve adapted for operation by a member on the track-way, a main shut-off valve between the main reservoir 85 and engineer's valve, air connections from the train pipe to the control valve and from the control valve to the main shut-off valve for actuating the latter upon operation of the control valve, a vent for said train pipe 90 air opened by said shut-off valve upon actuation of the same as aforesaid, a pressure actuated member for returning the control valve to its original condition, valve mechanism under control of the shut-off valve and 95 air connections therefrom to the control valve returning means.

2. An automatic train stop, comprising in combination with the main reservoir, train pipe and engineer's valve of an air brake 100 system, a control valve adapted for operation by a member on the track-way, a main shut-off valve between the main reservoir and engineer's valve, air connections from the train pipe to the control valve and from 105 the control valve to the main shut-off valve for actuating the latter upon operation of the control valve, a vent for said train pipe air opened by said shut-off valve upon actuation of the same as aforesaid, a pressure 110 actuated member for returning the control valve to its original condition, air connections from the main reservoir to the control valve returning means and valve mechanism in said air connections under control of the 115 shut-off valve.

3. An automatic train stop, comprising in combination with the main reservoir, train pipe and engineer's valve of an air brake 120 system, a control valve adapted for operation by a member on the track-way, a main shut-off valve between the main reservoir and engineer's valve, air connections from the train pipe to the control valve and from 125 the control valve to the main shut-off valve for actuating the latter upon operation of the control valve, a vent for said train pipe air opened by said shut off valve upon actuation of the same as aforesaid, a pressure actuated member for returning the control 130

valve to its original condition, valve mechanism under control of the shut-off valve and air connections therefrom to the control valve returning means, a power controlling member, fluid pressure operating means for operating said member and fluid pressure supply connections to said member under the control of the shut-off valve.

4. An automatic train stop comprising in combination, a main reservoir, a train pipe, an engineer's valve between the main reservoir and train pipe, a control valve arranged to be operated by a member on the track-way, a shut-off valve for closing the connection between the main reservoir and engineer's valve, connections from the train pipe to the control valve and from the control valve to the shut-off valve for operating said shut-off valve when the control valve is actuated, a vent for said train pipe air opened by said shut-off valve when the same is actuated by said train pipe air and an automatic cut-out valve interposed in the connections between the train pipe and control valve for rendering the control valve inoperative when the train pipe pressure is reduced by the manual control of the brakes.

5. An automatic train stop, comprising in combination, a main reservoir, a train pipe, an engineer's valve between the main reservoir and train pipe, a control valve arranged to be operated by a member on the track-way, a shut-off valve for closing the connection between the main reservoir and engineer's valve, connections from the train pipe to the control valve and from the control valve to the shut-off valve for operating said shut-off valve when the control valve is actuated, a vent for said train pipe air opened by said shut-off valve when the same is actuated by said train pipe air, and an automatic pressure controlling valve interposed in the connection between the train pipe and control valve for automatically controlling the flow of air to the shut-off valve.

6. An automatic train stop comprising in combination, a main reservoir, a train pipe, an engineer's valve between the main reservoir and train pipe, a control valve arranged to be operated by a member on the track-way, a shut-off valve for closing the connection between the main reservoir and engineer's valve, connections from the train pipe to the control valve and from the control valve to the shut-off valve for operating said shut-off valve when the control valve is actuated, a vent for said train pipe air opened by said shut-off valve when the same is actuated by said train pipe air, an automatic cut-out valve interposed in the connections between the train pipe and control valve for rendering the control valve inoperative when the train pipe pressure is reduced by the manual control of the brakes,

and an automatic pressure controlling valve interposed at a point in the connections between the train pipe and shut-off valve.

7. An automatic train stop, comprising in combination with the main reservoir, train pipe and engineer's valve of an air brake system, a shut-off valve controlling the communication between the main reservoir and engineer's valve, a pressure operated device for actuating said shut-off valve, air connections between the train pipe and said pressure actuated device, a control valve interposed in said connections and adapted to be operated by a member on the track-way, pressure operated mechanism for returning the control valve to its original condition, connections from the main reservoir to said pressure operated mechanism and valve mechanism under control of the shut-off valve for controlling flow from the main reservoir to said pressure operated mechanism.

8. An automatic train stop, comprising in combination with the main reservoir, train pipe and engineer's valve of an air brake system, a shut-off valve controlling the communication between the main reservoir and engineer's valve, a pressure operated device for actuating said shut-off valve, air connections between the train pipe and said pressure actuated device, a control valve interposed in said connections and adapted to be operated by a member on the track-way, pressure operated mechanism for returning the control valve to its original condition, connections from the main reservoir to said pressure operated mechanism, valve mechanism under control of the shut-off valve for controlling flow from the main reservoir to said pressure operated mechanism, a power controlling member and pressure actuated means for operating said power controlling member interposed in the air supply connections to the control valve operating mechanism.

9. In an automatic train stop, the combination with an air brake system including an engineer's valve for controlling application of the brakes, of a shut-off valve for rendering the engineer's valve inoperative, a control valve connected to the train pipe and operated by means on the trackway for operating said shut-off valve and effecting a service application of the brakes, and an emergency control valve for operating the shut-off valve and effecting an emergency application of the brakes.

10. In a system of the character described, the combination of a main reservoir, a train pipe, and an engineer's valve interposed between the reservoir and train pipe, a shut-off valve interposed between the reservoir and engineer's valve, a control valve for admitting air from the train pipe to the shut-off valve, and a compensating valve inter-

- posed between the train pipe and control valve having means for graduating the flow of air from the train pipe to said control valve.
- 5 11. In an automatic train stop, a train pipe and an engineer's valve for normally controlling the application of the brakes, a valve for rendering the engineer's valve ineffective, a control valve for venting the 10 train pipe to cause an application of the brakes, and an automatic compensating valve connected to the train pipe and control valve for regulating the rate of escape of air past said control valve.
- 15 12. In an automatic train stop, a train pipe and an engineer's valve for normally controlling the application of the brakes, a valve for rendering the engineer's valve ineffective, a control valve for venting the train 20 pipe to cause an application of the brakes, and a compensating valve interposed between the train pipe and control valve, said compensating valve having a valve member subjected to the train pipe pressure and governing the rate of flow of air to the control 25 valve.
13. In an automatic train stop, a train pipe and an engineer's valve for normally controlling the application of the brakes, a 30 valve for rendering the engineer's valve ineffective, a control valve for venting the train pipe to cause an application of the brakes, and a compensating valve interposed between the train pipe and control 35 valve, said compensating valve having a pressure-operated member subjected to train pipe pressure provided with a restricted passage for controlling the flow of air to said control valve.
- 40 14. In an automatic train stop, a train pipe and an engineer's valve for normally controlling the application of the brakes, a valve for rendering the engineer's valve ineffective, a control valve for venting the 45 train pipe to cause an application of the brakes, a cylinder in communication with said train pipe and having an outlet port in communication with said control valve, a piston in said cylinder subjected to the train 50 pipe pressure, and a slide carried by said piston covering the outlet port and provided with a diamond-shaped valve opening controlling said port.
- 55 15. In an automatic train stop, a train pipe and an engineer's valve for normally controlling the application of the brakes, a valve for rendering the engineer's valve ineffective, a control valve for venting the train pipe to cause an application of the brakes, a 60 cylinder in communication with said train pipe and having an outlet port in communication with said control valve, a piston in said cylinder subjected to the train pipe pressure, and a slide carried by said piston 65 and controlling the outlet port.
16. In combination with the train pipe of an air brake system, a compensating cylinder in communication with said train pipe and provided with an outlet port, a piston working in the cylinder and subjected to the 70 train pipe pressure, a slide carried by said piston and controlling the outlet port, and an automatic cut-out valve interposed between the train pipe and the compensating valve provided with an operating member 75 subjected to the train pipe pressure.
17. In combination with the main reservoir, a train pipe, and an engineer's valve of an air brake system, a shut-off valve interposed between the reservoir and engineer's 80 valve, means for operating said shut-off valve, a train controlling member, pressure actuated means for operating said train controlling member, and valve mechanism under control of the shut-off valve for admitting air under pressure from the main reservoir to the pressure actuated means.
18. In an automatic train stopping system, a main shut-off valve for shutting off a source of fluid under pressure, a piston normally subjected to said fluid under pressure, and adapted to be cut off from said fluid upon actuation of the shut-off valve, train 90 controlling means, a pressure actuated device for operating said train controlling means, 95 and a valve operated by the piston aforesaid for controlling flow of actuating fluid from the supply aforesaid to the pressure actuated device.
19. In an automatic train stopping system, a main shut-off valve for shutting off a source of fluid under pressure, a piston normally subjected to said fluid under pressure and adapted to be cut off from said fluid upon actuation of the shut-off valve, a train 100 controlling means, a pressure actuated device for operating said train controlling means, 105 a valve operated by the piston aforesaid for controlling flow of actuating fluid from the supply aforesaid to the pressure actuated device, and means for automatically venting the pressure on said piston when the 110 shut-off valve is closed.
20. In an automatic train stopping system, a main shut-off valve for shutting off a source of fluid under pressure, a piston normally subjected to said fluid under pressure and adapted to be cut off from said fluid upon actuation of the shut-off valve, train 115 controlling means, a pressure actuated device for operating said train controlling means, 120 a valve operated by the piston aforesaid for controlling flow of actuating fluid from the supply aforesaid to the pressure actuated device, means for automatically venting the pressure on said piston when the shut-off valve is closed, and means for automatically venting the pressure beneath the 125 piston when the shut-off valve is again opened.
- 130

21. In an automatic train stopping system, a shut-off valve having a supply passage therethrough, a valve member controlling flow through said passage, a cylinder having a port open to said passage and controlled by said valve member, a piston in said cylinder, a supply valve operated by said piston, pressure actuated train controlling means, and fluid pressure supply connections controlled by the piston operated valve. 50
22. In an automatic train stopping system, a shut-off valve having a supply passage therethrough, a valve member controlling flow through said passage, a cylinder having a port open to said passage and controlled by said valve member, a piston in said cylinder, a supply valve operated by said piston, pressure actuated train controlling means, fluid pressure supply connections controlled by the piston operated valve and pressure actuated means for operating the shut-off valve. 55
23. In combination with a main reservoir, a train pipe and engineer's valve, a shut-off valve having a passage providing communication between the reservoir and engineer's valve, a cylinder, a piston working in said cylinder, a valve carried by said piston and controlling the passage aforesaid, a vent in the cylinder controlled by the piston, a control valve connected with the train pipe, and air connections from said control valve to the head of the piston aforesaid. 60
24. In combination with a main reservoir, a train pipe and engineer's valve, a shut-off valve having a passage providing communication between the reservoir and engineer's valve, a cylinder, a piston working in said cylinder, a valve carried by said piston and controlling the passage aforesaid, a vent in the cylinder controlled by the piston, a control valve connected with the train pipe, air connections from said control valve to the head of the piston aforesaid, and manually operable means for actuating the shut-off valve. 65
25. In combination with a main reservoir, a train pipe and engineer's valve, a shut-off valve having a passage providing communication between the reservoir and engineer's valve, a cylinder, a piston working in said cylinder, a valve carried by said piston and controlling the passage aforesaid, a vent in the cylinder controlled by the piston, a control valve connected with the train pipe, air connections from said control valve to the head of the piston aforesaid, and manually operable means for actuating the shut-off valve. 70
26. In combination with a main reservoir, a train pipe and engineer's valve, a shut-off valve having a passage providing communication between the reservoir and engineer's valve, a cylinder, a piston working in said cylinder, a valve carried by said piston and controlling the passage aforesaid, a vent in the cylinder controlled by the piston, a control valve connected with the train pipe, air connections from said control valve to the head of the piston aforesaid, and manually operable means for actuating the shut-off valve. 75
27. In an automatic train stop, a control valve, pressure actuated means for testing the control valve, fluid pressure supply connections thereto and a check valve interposed in said fluid pressure supply connections. 80
28. In an automatic train stop, a control valve, pressure actuated means for testing the control valve, fluid pressure supply connections thereto and a check valve interposed in said fluid pressure supply connections. 85

JOHN S. CRAWFORD.
